NONREFILLABLE CONTAINER

Eduardo Alonso Planas, Habana, Cuba

Application March 21, 1945, Serial No. 583,865
In Cuba July 5, 1944

2 Claims. (Cl. 215—25)

1

This invention relates to new and useful improvements in a non-refillable container.

More specifically, the present invention relates to that type of container which cannot be filled except by special equipment to the end that a manufacturer of a liquid product can sell his product in the container without danger of the container being refilled by another to fraudulently imitate the aforesaid product. The container is made non-refillable by a device which is characterized by having a non-return valve in its spout controlled by gravity and a second non-return valve inwardly thereof controlled by a pendulum. The device must be taken apart to fill, and the device is provided with a seal which must be broken in order to refill the bottle, thereby denoting that it has been tampered with and filled with a fraudulent liquid if filled by other than the manufacturer.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure—

Fig. 1 is a fragmentary front view of the device of the present invention.

Fig. 2 is an axial section of the device of Fig. 1.

Fig. 3 is an inverted axial section, tilted, of the device showing it in liquid emptying position.

Fig. 4 is an outside tilted perspective view of the device.

Fig. 5 is a perspective view of the gravity valve of the device.

Fig. 6 is a side view of the pendulum valve of the device, parts being shown in section.

Fig. 7 is an enlarged section on the line 7—7 of Fig. 2.

Fig. 8 is a section on the line 8—8 of Fig. 2.

Fig. 9 is an inverted plan of a part of the pendulum valve.

Fig. 10 is a perspective view of a clamp ring forming part of the device.

The non-refillable device, according to this invention, comprises a circular plate 10 provided with a central port 11. This plate is adapted to rest on the top of a container 12 and to be secured thereto by a clamp ring 13. Clamp ring 13 is a well known type of split ring having a channelled annulus or groove 14 with a slot 15 at one end and a tongue 16 at the other end. The periphery of the plate 10 and the flange 17 of the container

2

fit in the groove 14 and the tongue 16 extends through the slot 15 and is bent, securing the parts together. The clamp ring may be further sealed by soldering the tongue 16 to the body of the ring, or the tongue may be of destructible material so that once it is unbent, it becomes broken and incapable of further use.

A collar 18 surrounds the port and extends from one side of the plate 10 and a spout 19 surrounds the port and extends from the other side of the plate 10. The spout 19 includes a cylindrical side wall 20 and a reduced nozzle 21. The spout 19 is partitioned interiorly by a wall 22 having a central orifice 23. A gravity valve 24 operates to control orifice 23. This valve includes a disc 25 adapted to rest on top of wall 22 over orifice 23, and wings 26 for guiding the disc 25. Thus when the device is in normal position, disc 25 closes orifice 23.

20 Port 11 is normally closed by a disc 27 resting on top of wall 10 over port 11. Disc 27 has a depending hook 28 and depending normally from this is a swingable weight or pendulum 29, the pendulum including a disc 30 parallel normally to disc 27 but spaced therefrom. Nozzle 21 is closed by a cap 31 which may be pulled off when it is desired to empty the container.

The operation of the device is as follows:

30 The manufacturer of a liquid product fills the container 12, for instance a bottle, with his product, then disposes the device thereon and applies the ring 13 as aforesaid. He then sells the container and product with the stipulation that the container is to be returned.

35 The purchaser of the container and product, in order to remove the product from the container, need only remove cap 31 from the device and tip the container upside down to an inclined position as shown in Fig. 3, whereupon the valve 24 will fall by gravity until it rests against the top wall of the spout, and the disc 27 will fall by gravity to the inclined position shown in Fig. 3, the disc 30 also seeking a similar position with one side of its edge resting against the underside of the plate 10. The pendulum, due to the inclined position of the device, will swing to one side, holding the disc 30 as aforesaid so that neither disc 30 nor disc 27 can close port 11. The wings 26 prevent valve 24 from closing the nozzle 21. Thus the liquid will pour out of the container.

Should only part of the contents of the container be removed, upon returning the container and device to normal upright position, the two valves will close their respective ports and seal

the container against liquid evaporation or contamination, thus supplementing the cap 31.

It is impossible for the user of the container, usually a private individual, to refill the container without destroying the ring 13. Should anyone but the original manufacturer destroy the ring 13, or injure it, with the purpose in mind of filling the container and fraudulently passing the product off as the product of the original manufacture, it will be apparent at a glance to a prospective purchaser that the device has been tampered with and he will not make the purchase.

When the original manufacturer gets the container returned empty, he destroys the ring 13 and on refilling the container, puts a similar ring back. Thus the container may be used over and over again.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A non-refilling bottle closure, comprising in combination a circular apertured plate adapted to be seated on the mouth of the bottle, a cylindrical spout extending from one side of the plate in a direction away from the bottle and fixed thereto and open at the free end, an apertured flange fixed within the spout, a non-apertured disc movable between the plate and the flange within the spout, a non-apertured disc movable between the flange and the open end of the spout within the spout, said second non-apertured disc being provided with means for spacing it from the free end of the spout, a pendulum weight movably suspended from the first named non-apertured disc and extending away from the spout, a third disc associated with said pendulum weight and mounted thereon closely adjacent the apertured plate, whereby upon tilting of the bottle, said first non-apertured disc and said last non-apertured disc will engage the apertured plate from opposite sides and at diametrically

spaced points, said spout, apertured plate and discs constituting a self-contained assembly adapted to be supported on the mouth of the bottle, and a sealing ring circumferentially engaging said apertured plate and mouth and holding the assembly in position on the bottle.

2. In a non-refillable bottle closure, the combination of a plate adapted to be seated on the mouth of the bottle, a cylindrical spout secured at one end to said plate and extending therefrom in a direction away from the bottle, an apertured flange fixedly within the spout, a non-apertured valve disc movable between the plate and the flange within the spout, a non-apertured valve disc movable between the flange and the free open end of the spout within the spout, said second named valve disc being provided with means for spacing it from the free end of the spout, a pendulum weight movably suspended from the first named valve disc and extending away from the spout, a third disc associated with the pendulum weight and mounted thereon closely adjacent the apertured plate, whereby upon tilting of the bottle, said first named valve disc and said last named disc will engage the apertured valve plates from opposite sides and at diametrically spaced points, said spout, apertured plate and discs forming a self-contained assembly adapted to be supported on the mouth of the bottle, and a sealing band circumferentially engaging the mouth and the apertured plate and provided with a tongue projected through a slot in said band when said band is applied circumferentially to said plate and mouth.

35 EDUARDO ALONSO PLANAS.
